UNITED STATES PATENT OFFICE

164,605

CARD GAME PLAYING DEVICE OR SIMILAR ARTICLE

Theodore Romanchek, Los Angeles, Calif.

Application January 29, 1949, Serial No. 563

Term of patent 14 years

(Cl. D34—13)

To all whom it may concern:

Be it known that I, Theodore Romanchek, a citizen of the United States residing at Los Angeles, in the county of Los Angeles and State of California, have invented a new, original, and ornamental Design for Card Game Playing Device or Similar Article, of which the following is a specification, reference being had to the accompanying drawing, forming a part thereof.

Fig. 3 is a bottom plan view thereof.

I claim:

The ornamental design for a card game playing device or similar article, substantially as shown.

THEODORE ROMANCHEK.
